UNITED STATES PATENT OFFICE

147,608

DESIGN FOR AN AIRPLANE CONTROL WHEEL

Howard A. Benzel, Lancaster, N. Y., assignor to
Scott Aviation Corporation, Lancaster, N. Y., a
corporation of New York

Application April 1, 1946, Serial No. 128,152

Term of patent 14 years

(Cl. D14—30)

To all whom it may concern:

Be it known that I, Howard A. Benzel, a citizen of the United States, residing at Lancaster, in the county of Erie and State of New York, have invented a new, original, and ornamental Design for an Airplane Control Wheel, of which the following is a specification, reference being had to the accompanying drawing, forming part thereof.

In the drawing:

Fig. 1 is a front elevational view of an airplane control wheel, showing my design;

Fig. 2 is a top plan view; and

Fig. 3 is a side elevational view thereof.

I claim:

The ornamental design for an airplane control wheel, substantially as shown.

HOWARD A. BENZEL.
